UNITED STATES PATENT OFFICE.

RALPH E. HARRIS, OF NEW ORLEANS, LOUISIANA.

POCKET BATHING SUIT.

Application filed August 4, 1927. Serial No. 210,588.

This invention relates to bathing suits of the one-piece type, and has for one of its objects to provide an article of this character with a pocket which shall constitute an integral part thereof and into which it may be readily folded for convenience in carrying it to and from the bathing beach or pool.

With the foregoing and other objects in view, the nature of which will appear as the description proceeds, the invention consists of the construction, combination and arrangement of parts hereinafter fully described and claimed, and illustrated in the accompanying drawings, wherein:

15 Figure 1 is a view partly in side elevation and partly in vertical section of a bathing suit equipped with a pocket in accordance with my invention,

20 Figure 2 is a rear elevation illustrating the bathing suit partly folded for insertion in the pocket,

Figure 3 is a sectional view taken on the vertical planes indicated by the line 3—3 of Figure 2, and

25 Figure 4 is a sectional view illustrating the bathing suit in the pocket.

Referring in detail to the drawing, 1 designates the shirt, 2 the trunks and 3 the skirt of a one-piece bathing suit of the type now 30 generally worn by women, the skirt being secured at its upper edge to the waistline of the shirt, as shown at 4.

In accordance with my invention, the bathing suit is provided with a pocket 5 which 35 is preferably made from light weight waterproof material, such as silk rubber or sheet rubber. If desired, the pocket may be made from silk. The pocket 5 comprises a rear side 6, a front side 7 and a flap 8 extending 40 from the upper edge of the rear side and provided with a button-hole 9. A button 10 is carried by the rear side 6 and a button 11 by the front side 7. The buttons 10 and 11 are 45 similar and made of metal. The buttons each consists of a shank and heads at the ends of the shank, and they are removably secured in place by being passed through holes 12 and 13. The pocket 5 is provided with a hand strap 14 which is preferably made from the same material employed in the manufacture of the 50 pocket and which is secured at its ends to the upper ends of the pocket.

The pocket 5 is after being turned inside out secured in an inverted position to the inner 55 side of the skirt 3, and it may be positioned at the front side, rear side or one of the lateral

sides of the skirt. The pocket 5 is secured to the skirt 3 with its rear side 6 in contact with the skirt, and this side of the pocket may be stitched, as shown at 15, or secured in any 60 other suitable manner to the skirt. The flap 8 is arranged within the pocket 5 and secured to the button 10, and the hand strap 14 is also preferably arranged within the pocket.

As the pocket 5 is made from light weight 65 material, and owing to the manner in which it is secured to the bathing suit, it will not make the bathing suit uncomfortable to wear, and it will not interfere with or retard the motion of the bather in the water. When 70 the bather wishes to place the bathing suit in the pocket 5, the skirt 3 is first raised into the position shown in Figures 2 and 3 so as to position the pocket at the outer side of the skirt. The flap 8 is then withdrawn from 75 the pocket 5, the suit is then folded upon the pocket, and thereafter the pocket is turned right side out so as to position the suit within the pocket. The flap 8 is secured to the button 10 if it is desired to carry the pocketed 80 suit by the hand strap 14. If it is desired to carry the pocketed suit in a rolled condition, the pocketed suit is first rolled and thereafter the flap 8 is secured to the button 11. The buttons 10 and 11 are removed prior to 85 wringing the suit so as to prevent them from injuring the pocket 5 or the suit and so as to prevent them from being injured during the wringing of the suit. While the pocket 5 is 90 shown applied to a woman's bathing suit, it is to be understood that it may be also used in connection with men's bathing suits.

It should be understood that the drawing is merely illustrative and does not pretend to give exact proportions. Furthermore, the 95 said drawing is illustrative of a preferred construction, it being my expectation that various changes and modifications may be made without departing from the spirit and scope of my invention.

What is claimed is:—

In combination with a bathing suit having a trunk portion, and skirt portion secured to said trunk portion, a pocket secured to the inner side of the skirt portion and into which said trunk and skirt portions are adapted to be placed when folded, a flap carried by the pocket and adapted to close it, and means to hold the flap in closed position.

In testimony whereof I affix my signature.

RALPH E. HARRIS.
